LOCKING BRIDGE TOP STOP

Alfred E. Carlile, Meadville, Pa., assignor to Talon,
Inc., a corporation of Pennsylvania

Application August 11, 1941, Serial No. 406,245

7 Claims. (Cl. 24—205)

This invention relates to slide fasteners and, in particular, to the provision of a new and improved bridge top stop for slide fasteners.

It is the object of this invention to provide a bridge top stop for slide fasteners which embodies means cooperating with the slider of the fastener, in its uppermost or closed position, yieldingly to maintain the slider in the aforesaid closed position for preventing accidental opening of the fastener, in addition to the means commonly possessed by such bridge top stops whereby they connect and maintain the upper ends of the stringer tapes of the fastener, above the rows of the interlocking fastener members, in predetermined slightly spaced relationship.

In the application of slide fasteners to garment placket and other closure openings where it is desired that both ends of the closure opening be closed, a common connection is often provided between the upper ends of the stringer tapes by means of an end fitting commonly known as a bridge top stop secured between and to the adjacent edges of the stringer tapes and by means of which these adjacent edges of the stringer tapes are maintained in predetermined slightly spaced relation with respect to one another.

While in practice slide fasteners used on dress placket openings and some other closure openings have not been provided with locking sliders, it is desirable that some means be provided to prevent the slider from "walking down" from its fully closed position. While automatic lock sliders are used extensively on slide fasteners for many garment closures, their use on fasteners for dress plackets and the like is objectionable because of the extra bulkiness or thickness of the slider, and also because of the additional expense of the automatic locking mechanism. As a result of my invention, conventional non-locking sliders may still be used and the slider is nevertheless held in its fully closed position by the bridge top stop. Thus, accidental opening of such fasteners is prevented without any undesirable projections on the slider and without the expense of other locking means.

Since side dress placket applications require that the closure opening be closed at both ends, it is impossible, with satisfaction, to use any of those prior art top stop constructions which comprise a separate and independent stop member on each stringer adapted to limit upward movement of the slider and also, in some cases, provided with means intended to prevent accidental downward movement of the slider. These

known top stop members are unsatisfactory for such dress applications, first, because they provide no common connecting means for the upper ends of the slide fastener stringer tapes. They are unsatisfactory also since they are permitted to tilt, because of their independence of one another, whereby to bind or otherwise become so fouled in the slider, or its parts, as to make it difficult, and sometimes impossible, to open the fastener without damaging the garment to which the fastener is attached. Since the upper ends of the locking members of the locking bridge top stops are, in each embodiment of this invention, connected and maintained in predetermined spaced relationship all of the above disadvantages are totally obviated.

Also, according to this invention, all of the above described disadvantages of the prior art are totally eliminated by the use, with a fastener provided with a relatively flat non-locking slider, of my new and improved bridge top stop construction which, in addition to the tape holding portions is provided with means yieldingly engaging the slider in its uppermost, closed, position and yieldingly connecting it to the stationary bridge top stop whereby accidental opening of the fastener by reason of the above described "walking down" of the slider is effectively prevented. Since the connection between the bridge top stop and slider is yielding, it may readily overcome by the application of manual force to the slider, in conventional manner, to open the slide fastener. Thus the improved bridge top stop provides controlled resistance to downward movement of the slider from its uppermost locked position, which resistance is sufficient to prevent accidental opening of the fastener without impairment of the ease of operation of the fastener.

These and other objects and advantages of the invention will appear from the following description taken in conjunction with the accompanying drawing, which forms a part thereof, and will be pointed out in the appended claims.

In the drawing:

Fig. 1 is a fragmentary perspective view of a conventional slide fastener provided with an improved bridge top stop, according to this invention;

Fig. 2 is a fragmentary plan view of the fastener shown in Fig. 1 with the slider in section, and the parts in unlocked position;

Fig. 3 is a view similar to Fig. 2 but showing the parts in locking position;

Fig. 4 is a view in perspective of the bridge top stop of Fig. 1;

Fig. 5 is a view similar to Fig. 3 but showing a modified form of bridge top stop, according to this invention;

Fig. 6 is a view similar to Fig. 4 of the bridge top stop shown in Fig. 5;

Fig. 7 is a view similar to Figs. 3 and 5 of a second modified form of bridge top stop, according to this invention; and

Fig. 8 is a view similar to Figs. 4 and 6 of the second modified form of bridge top stop shown in Fig. 7.

In Fig. 1 of the drawing wherein a bridge top stop, according to this invention, is shown applied to the conventional slide fastener, the fastener includes a pair of stringers generally designated 11 and 12. Each stringer comprises a flexible stringer tape 14 provided with a reinforced edge 15 which carries a row of predeterminedly spaced cooperating interlocking fastener members 16 clamped or otherwise secured thereto in known manner. The lower ends of the reinforced edges 15 of the tapes 14 are connected, in conventional manner, by a suitable bottom end fitting or bottom stop such as that shown in Fig. 1 and therein designated 17. Slidable along the rows of the interlocking fastener members 16 for progressively engaging and disengaging same, for closing and opening the fastener, is a slider generally designated 18.

The slider 18, as shown in Fig. 1, is formed by a pair of similar wings 19 connected at their upper ends by a wedge forming neck 20. Each wing is provided with marginal guide flanges 21 which cooperate with the inclined side surfaces of the wedge or neck 20 to form an upwardly diverging, generally Y-shaped, guide channel between the wings 19 for guiding the interlocking fastener members 16 progressively into and out of interlocking relation as shown, for instance, in Figs. 2 and 3. The forward or outer wing 19 (not shown in Figs. 2, 3, 5 and 7) is provided with a pair of pull tab supporting lugs 22 in the form of upstanding loops extending outwardly or forwardly from the wing 19. The slider is provided with the conventional pull tab, generally designated 23, which is of plate-like form and which is provided at its outer end with a thong receiving aperture 24. Its inner end is provided with a pair of slots 25 between a central tongue 26 and a pair of legs 27, each of which legs 27 is provided with a projection or trunnion 28 extending toward the tongue 26. These projections or trunnions 28 extend beneath the loop-like lugs 22 and pivotally secure the inner end of the pull tab 23 to the slider 18.

The preferred embodiment of locking bridge top stop, according to this invention, is shown in Figs. 1 to 4 and is therein generally designated 30. It comprises a pair of generally tubular tape holding members 31 adapted to be clamped or otherwise secured to the reinforced edge portions 15 of the respective stringers. These tape holding members are relatively inflexible because of their generally tubular section but are connected at their upper ends by a substantially flat transverse neck or bridge portion 32 which is substantially more resilient than the tape holding members 31 by reason of its simple relatively flat section. This bridge portion 32 effectively maintains the spacing between the upper ends of the tape holding portions 31 while, by reason of its flexibility and resiliency, permitting substantial movement of the lower, or free ends of the tape

holding portions 31. Hence, at their lower ends each tape holding portion 31 is provided with an inwardly directed extension or projection 33 which, by reason of its cooperation with the neck or wedge 20 of the slider, as shown in Figs. 2 and 3, may be termed locking members. Since these projections or locking members 33 are spaced substantially from the yielding or resilient bridge member 32, they may be forced apart by the neck or wedge 20 of the slider in its upward movement, as shown in Fig. 2, with concurrent flexing of the bridge portion 32 as shown in that figure.

After the neck or wedge 20 of the slider 18, has moved further upwardly, as shown in Fig. 3, these projections or locking members 33 will return to their normal unstressed relative positions, as shown in Fig. 3. When the locking members or projections 33 are in this position, and when the wedge 20 of the slider 18 is confined therebetween, as shown in Fig. 3, the cooperation between the bridge top stop 30 and the wedge 20 of the slider 18 is sufficient to prevent accidental downward movement of the slider to open the fastener. However, when it is desired to open the fastener, it is merely necessary manually to engage the pull tab 23 of the slider and pull it downwardly from the position shown in Fig. 3 to and beyond the position shown in Fig. 2 between which positions the neck or wedge 20 of the slider will force the locking projections or locking members 33 apart sufficiently to permit the slider to be freed from its yielding connection with the bridge top stop.

An alternative form of locking bridge top stop, according to this invention, is shown in Figs. 5 and 6 and is therein generally designated 40. This bridge top stop 40 is provided with tape holding portions 41 which are of similar section to the above described tape holding portions 31. These tape holding portions 41 are connected by a transverse neck or bridge portion 42 which is of curved section and therefore relatively inflexible whereby no substantial flexing of the tape holding portions 41 is permitted. For this reason, the locking projections or locking members 43 comprise inwardly directed somewhat curved tab-like prongs slit from the central part of the tape holding portions 41 of the bridge top stop 40. These prong-like locking projections 43, because of their flat section, are extremely spring-like and yield readily from their normal unstressed position (Fig. 6) under the spreading force exerted by the wedge or neck 20 of the slider 18 (as shown in Fig. 5) to permit the slider 18 to be manually pulled up to its uppermost position as shown in Fig. 5. In this uppermost position, the wedge or neck 20 of the slider 18 is clampingly connected yieldably to the bridge top stop 40 by the clamp-like locking members 43, as shown in Fig. 5. The clamping force of the locking members 43, in this position, is sufficient to prevent accidental downward movement of the slider 18. However, the neck or wedge 20 of the slider 18 may readily be withdrawn from its position between the locking members 43 by the application of slight tension to the pull tab 23 of the slider 18.

A second modification of the invention is shown in Figs. 7 and 8, and is therein generally designated 50. It comprises a pair of tape holding portions 51 similar to the above described tape holding portions 41 of the bridge top stop 40. These tape holding portions 51 are connected by a transverse neck or bridge portion 52 which

is substantially inflexible and which is similar to the above described portion 42 of the bridge top stop 40. The locking members, extensions or projections, are designated 53 and are similar to the above described locking projections 43, save that they are somewhat larger and are disposed below the tape holding portions 51, being formed as prolongations of the tape holding portions 51 instead of being cut out therefrom as are the locking members 43 of the embodiment of Figs. 5 and 6. Because of their length and because of their relatively flat section and their curvature from end to end, these locking members or projections 53 are spring-like and clamp-like and are readily spread apart from their normal unstressed position shown in Fig. 8 by upward movement of the neck or wedge 20 of the slider 18 therebetween to the position shown in Fig. 7. In this position, the slider 18 is yieldingly connected to the bridge top stop 50 by the clamping engagement between the locking members 53 and the inclined side surfaces of the neck or wedge 20 of the slider 18. The clamping force exerted by the locking members 53 is sufficient, of course, to prevent accidental separation of the slider 18 and top stop 50 while manual application of tension to the pull tab 23 of the slider 18 will readily cause the neck or wedge 20 to spread the yielding locking members 53 apart in order that the neck or wedge 20 of the slider may pass downwardly therebetween and therebeyond to free the slider from the locking top stop 50.

From the above description it will readily appear that I have provided a new and improved locking top stop particularly adapted to dress placket applications and the like wherein it is desired to achieve a slide fastened closure which is closed at both ends and which embodies a slide fastener with a flat, non-locking slider, the cooperation of the bridge top stop with the slider providing controlled resistance to opening of the fastener in order effectively to prevent accidental opening of the fastener while obviating the necessity of any undue bulk or expense as a result of the use of locking sliders.

It is, of course, to be understood that the above described structure is merely illustrative and in nowise limiting and that I desire to comprehend within my invention all modifications included within the scope of the appended claims.

Having thus fully described my invention, what I claim as new and desire to secure by Letters Patent is:

1. A locking bridge top stop for slide fasteners comprising a pair of connected stringer tape engaging members adapted to maintain the complementary tapes of a slide fastener in predetermined relation, and means on said members engageable with the slider of said fastener in its uppermost position for yieldingly connecting said slider and said top stop to prevent accidental opening of said slide fastener.

2. A locking bridge top stop for slide fasteners comprising a pair of stringer tape engaging members connecting at their upper ends and adapted to maintain the complementary tapes of a fastener in predetermined relation, and means on said members clampingly engaging the neck of the slider of the fastener in its uppermost position for yieldingly connecting said slider and said top stop to prevent accidental opening of said slide fastener.

3. In combination with a slide fastener including a pair of stringer tapes each having a row of interlocking fastener members on one edge, and a slider slidable on said rows of interlocking fastener members for progressively engaging and disengaging said fastener members to close and open said fastener; a bridge top stop comprising a pair of tape holding members connected at their upper ends and secured to adjacent edges of said tapes above the rows of interlocking fastener members for maintaining said upper tape ends in predetermined relation, and means on said top stop cooperating with said slider in its uppermost position for yieldingly connecting said slider with said top stop to prevent accidental opening of said fastener.

4. In combination with a slide fastener including a pair of complementary stringer tapes each having a row of interlocking fastener members on one edge, and a slider slidable on said rows of interlocking fastener members for progressively engaging and disengaging said fastener members to close and open said fastener, said slider comprising a pair of wings connected at their upper ends by a neck; a bridge top stop comprising a pair of relatively inflexible tape holding members connected at their upper ends by a relatively flexible bridge portion, said tape holding members being secured to adjacent edges of said tapes above the rows of interlocking fastener members for maintaining said upper tape ends in predetermined relation, and projections on said tape holding members yieldingly engaging the neck of said slider in its uppermost position for yieldingly connecting said slider with said top stop in the closed position of said fastener to prevent accidental opening of said fastener.

5. In combination with a slide fastener including a pair of complementary stringer tapes each having a row of interlocking fastener members on one edge and a slider slidable on said rows of interlocking fastener members for progressively engaging and disengaging said fastener members to close and open said fastener, said slider comprising a pair of wings connected at their upper ends by a neck; a bridge top stop comprising a pair of relatively inflexible tape holding members connected at their upper ends by a relatively inflexible bridge, said tape holding members being secured to adjacent edges of said tapes above the rows of interlocking fastener members for maintaining said upper tape ends in predetermined relation, and a pair of yieldable prong-like locking projections on said tape holding members clampingly engaging the neck of said slider in its uppermost position for yieldingly connecting said slider with said top stop in the closed position of said fastener to prevent accidental opening of said fastener.

6. The combination defined in claim 5, said locking projections being disposed between said tape holding members and comprising yieldable prong-like projections struck out from said tape holding members.

7. The combination defined in claim 5, said locking projections comprising downwardly extending prolongations of said tape holding members forming spring-like spreadable clamping arms closely engaging the inclined side surfaces of the slider neck in the uppermost position of the slider.

ALFRED E. CARLILE.
